DRIER FURNACE

Henry C. French and Herman C. Frentzel, Jr.,
Milwaukee, Wis., assignors to The Heil Co.,
Milwaukee, Wis., a corporation of Wisconsin

Application December 15, 1934, Serial No. 757,680

7 Claims. (Cl. 158—1)

The present invention relates in general to improvements in the art of heating, and relates more specifically to improvements in the construction and operation of furnaces especially adapted for use in conjunction with driers.

Generally defined, an object of the invention is to provide an improved furnace which is simple and compact in construction, and which is, moreover, highly efficient in operation.

It has heretofore been common commercial practice to utilize oil-burning furnaces to supply heat to rotary hay driers and the like, and due to the intense heat created by the oil burners, considerable difficulty has been encountered in preventing the fire-brick arches from burning and thus introducing a serious fire hazard. With these prior furnaces, it has also been impossible to accurately control the temperature of the gases of combustion which were utilized for drying purposes, and various other objections inherent in the prior drier furnaces cooperated with the defects stated, to make the former heating devices very unsatisfactory.

It is a more specific object of the present invention to provide an improved drier furnace of the above-mentioned type, which obviates the defects of the prior devices of this character, and which is extremely durable and effective in operation.

Another specific object of the invention is to provide an improved furnace combustion chamber which is effectively protected against destruction by the heat of combustion, and wherein tempered air is delivered to the combustion zone.

Still another specific object of the invention is to provide an improved furnace especially adapted to deliver accurately regulated quantities of heated gas at accurately controlled temperatures, to a hay, forage, or garbage drier or the like.

A further specific object of the invention is to provide improved instrumentalities for controlling the heat of combustion created in an oil-burning furnace or the like.

An additional specific object of the invention is to provide a furnace structure of extreme simplicity and of great durability, which may be manufactured and operated at minimum cost.

These and other objects and advantages will be apparent from the following detailed description.

A clear conception of an embodiment of the several improved features, and of the mode of constructing and of operating drier furnaces built in accordance therewith, may be had by referring to the drawings accompanying and forming a part of this specification, in which like

reference characters designate the same or similar parts in the various views.

Fig. 1 is a side elevation of one of the improved furnaces, showing the same cooperating with a fragment of a rotary hay drier; 5

Fig. 2 is an end view of the furnace, looking toward the gas delivery end thereof;

Fig. 3 is a central, longitudinal section through the furnace and drier fragment, taken along the line 3—3 of Fig. 4; 10

Fig. 4 is a transverse vertical section through the furnace, taken along the line 4—4 of Fig. 1;

Fig. 5 is a fragmentary horizontal section through the fuel inlet side of the furnace, taken along the line 5—5 of Fig. 4; and 15

Fig. 6 is an enlarged fragmentary side view of a portion of the air inlet control mechanism.

While the invention has been shown herein as being specifically applied to an oil-fixed heating furnace for hay driers or the like, it is not desired to unnecessarily restrict the scope by such specific disclosure since some of the features may obviously be more generally applicable to other types of heating appliances utilizing other types of fuel such as gas. 20

Referring to the drawings, the improved furnace comprises in general a substantially annular fire-brick wall 8 cooperating with fire-brick end walls 9, 10 to form a cylindrical combustion chamber 11; a structural metal support 12 for the walls 8, 9, 10; a casing 13 cooperating with the support 12 to form a cooling air duct 14 which connects with the combustion chamber 11 through one or more tangential passages 15; and a series of adjustable fuel supply nozzles 16 for injecting regulated quantities of fuel oil into the chamber 11 through expanding tangential ducts 17. 30

While the major portions of the walls 8, 9, 10 may be formed of relatively standard fire-brick, 40 the portion of the wall 8 adjoining the passage 15 and duct 17 may be constructed of other refractory material. The end wall 9 nearest the injection nozzles 16 may be provided with a central sight opening 18, while the opposite end wall 10 has a relatively large gas outlet flue 19 communicating centrally with the chamber 11, and both of the end walls 9, 10 may be provided with insulating jackets 20, as shown in Figs. 3 and 5, which may either be filled with insulating material or left open to the duct 14. 45

The gas outlet flue 19 has a tempering air inlet control valve 21 associated therewith, and also has a comminuted hay supply hopper 22 near the gas delivery end thereof, as shown in 55

Figs. 1, 2, and 3. The hopper 22 communicates with a distributing and cut-off rotor 23 which has flexible blade portions 24 for preventing breakage of the blades or choking of the inlet in case obstructive material is admitted from the hopper 22. An inclined spout 25 communicates with the rotor chamber of the supply hopper 22 and is directed toward the delivery end of the flue 19. This delivery end of the flue 19 is in open communication with the central portion of a rotary drier drum 26 revolvably supported upon rollers 27, and the joint between the ends of the flue 19 and drum 26 is sealed by a flexible plate 28 and packing 29.

15 The cooling air duct 14 formed by the outer casing 13 and surrounding the wall 8 is provided with an air inlet 30 at the side of the furnace, said inlet 30 having a series of inlet openings 31 controllable in effective area, by means of a slide 32, as clearly shown in Figs. 1, 4, and 6. The air inlet 30 also has one or more sight openings 33 extending directly into the combustion chamber 11, and the air flowing from the inlet 31 through the peripheral duct 14 effectively cools the wall 8 while at the same time absorbing heat so as to effect pre-heating. The pre-heated air delivered into the lower portion of the combustion chamber 11 in a tangential direction is intimately mixed with the fuel delivered from the nozzles 16 and produces a whirling, highly combustible mixture, which is ignited and advances helically toward the outlet flue 18. By admitting the air supply at the lower portion of the chamber 11 beneath the oil injecting nozzles, the lower portion of the fuel inlet end of the wall 8 is protected against undesirable oil deposits, and thorough mixing of the atomized oil and pre-heated air is insured.

The fuel injection nozzles 16, four in number, are controllable independently of each other in order to provide a highly flexible fuel supply regulating system. This, combined with the air control afforded by the slide 32, permits accurate control of the combustion and of the combustion gas temperatures. The auxiliary air supply valve 21 permits further control of the temperature and volume of the drying gases, thereby providing highly effective and conveniently manipulable control means for the furnace. The nozzles 16 may be removably and adjustably supported on a bracket 34 secured to the side of the furnace near the manipulating handles for the slide 32, so that one attendant may conveniently operate these control elements, as well as the valve 21, and the cooling of the outer casing 13 by the air in the duct 14, as well as the insulating jackets 28, prevents excessive or dangerous heating of the exposed surfaces of the furnace assemblage.

During normal operation of the improved furnace, the nozzles 16 are adjusted so as to admit any desired quantities of fuel such as oil, and the slide 32 is set to admit sufficient air to properly support combustion of the fuel. Since the conditions within the combustion chamber 11 are ascertainable through the openings 18, 33, the operation of the furnace may be thus readily controlled. The cold air admitted from the inlet passage 31 to the annular duct 14 effectively cools the entire wall 8 of the furnace and becomes pre-heated before being delivered through the tangential passage 18 into the combustion chamber 11. The burning mixture of fuel and air advances through the chamber 11 in the form of a swirling vortex, as indicated by the dot-and-dash line in Fig. 3, and as the gases of combustion enter the 70 outlet flue 18, complete combustion has taken

place. The highly heated gases of combustion passing through the flue 18 may be tempered by the addition of air past the valve 21, and are subsequently intimately mixed with the comminuted material delivered into the advancing stream by the feed rotor 23 and spout 25. The mixture of hot gas and comminuted material subsequently passes through the drier 26 for final treatment.

From the foregoing description, it will be apparent that the present invention provides an extremely simple but highly efficient furnace for delivering heated gases of combustion to a drier or the like. The furnace walls, which are subjected to the greatest heat, are effectively protected against destruction by over-heating, and the air which is thus utilized to cool the furnace walls is simultaneously pre-heated before admission thereof to the combustion chamber. The quantity of gases of combustion, as well as the temperature thereof, may be conveniently regulated by adjustment of the fuel supply nozzles 16 and of the air inlet control slide 32 and auxiliary valve 21, thereby not only insuring complete combustion of the fuel, but also providing a simple control for the heat delivered to the drier. The furnace is especially applicable to a drier of the rotary type since it can be conveniently positioned so as to cooperate with such a drier and with the mechanism for feeding the material thereto. While the end walls 8, 18 have been shown as being jacketed with insulating jackets 28, these jackets may be left open so as to effect additional cooling of the end walls by the entering air which supports combustion. The improved furnace has proven highly effective and unusually durable in commercial operation and can be manufactured and sold at relatively moderate cost.

It is to be noted, that the air admitted to the combustion chamber through the tangential inlet 15, may be utilized for the dual purpose of supporting combustion within the chamber 11 and of tempering the final gases of combustion. The control valve 21 may if desired, be utilized only in emergency cases, and the temperature of the final gases may be regulated solely by controlling the quantity of air admitted through the openings 31 to the inlet 15. The combustion chamber 11 must, however, be of sufficient length to insure complete combustion of the gases before reaching the outlet flue 18, and such complete combustion within a relatively short chamber 11, is obtained by disposing the furnace horizontally rather than vertically. While this horizontal disposition of the furnace would normally be objectionable due to the fact that the upper confining wall is subjected to intense heat, the improved cooling arrangement overcomes this objection and protects these heated walls against undesirably rapid deterioration.

It should be understood that it is not desired to limit the present invention to the exact details of construction and to the precise mode of operation herein shown and described, for various modifications within the scope of the claims may occur to persons skilled in the art.

What is claimed as the invention is:

1. In a furnace, a wall forming a substantially cylindrical combustion chamber having a restricted gas outlet at one end thereof, nozzle means for injecting variable quantities of fuel only into the end of said chamber remote from said outlet and in a tangential direction, means forming an annular unobstructed conduit for conducting air around said wall throughout the

- entire length of said chamber, said conduit having an outlet end formed to inject said air tangentially into said chamber only adjacent the place of fuel injection so as to produce a vortex 5 of gas traveling toward said outlet and the inlet end of said conduit having a series of air supply openings extending throughout the length of said wall, and a slide for controlling the effective area of said air supply openings.
- 10 2. In a furnace, a wall forming an elongated combustion chamber circular in cross section and having a restricted central outlet at one end thereof, nozzle means for injecting fuel into said chamber only remote from said outlet and in a tangential direction, means forming an annular unobstructed conduit for conducting air around said wall, said conduit having its outlet end formed to inject said air into said chamber only adjacent the place of fuel injection and the 15 inlet end of said conducting means having a series of air supply openings extending throughout the length of said wall, and adjustable means for varying the effective area of said air supply openings.
- 20 3. In a furnace, a wall forming a substantially horizontal combustion chamber circular in vertical cross section and having an axial restricted central outlet at one end thereof, nozzle means for injecting fuel into said chamber only remote from said outlet and in a single tangential direction above the chamber bottom, means forming a single unobstructed annular conduit for conducting air around the exterior of said wall, said conduit having its outlet end formed to inject 25 said air tangentially into said chamber around the admitted fuel and the inlet end of said conduit having a series of air admission openings extending horizontally along the exterior of said wall, and means for varying the effective area 30 of said air admission openings.
- 25 4. In a furnace, a substantially horizontal annular wall forming a combustion chamber circular in vertical cross section and having a hot gas outlet at one end thereof, nozzle means for injecting fuel into said chamber only remote from said outlet and only in a single tangential direction considerably above the chamber bottom, means forming an annular unobstructed conduit for conducting air around the exterior of said wall, said conduit having its outlet end formed to inject said air tangentially into said chamber only beneath the point of fuel admission and the 35 inlet end of said conduit having air admission openings extending in series along the exterior 40
- of said wall, and means for varying the effective area of said air admission openings.
- 45 5. In a furnace, an annular wall forming a substantially horizontal combustion chamber circular in vertical cross section and having an axial restricted hot gas outlet at one end thereof, nozzles for injecting fuel into the opposite end of said chamber only considerably above the chamber bottom and in a single tangential direction, an outer casing forming an annular unobstructed air conducting conduit in contact with said wall and extending around and along the latter, the air delivery end of said conduit being directed tangentially into said chamber only beneath said nozzles and the inlet end of said conduit being provided with a series of fresh air admission openings, and means for simultaneously varying the effective areas of all of said 50 openings.
- 50 6. In a furnace, an annular wall forming a horizontal cylindrical combustion chamber having a restricted axial outlet for hot gases of combustion at one end thereof, a series of nozzles for injecting fuel tangentially into said chamber only near its opposite end and some distance above the chamber bottom, an outer casing forming a single annular air conducting conduit extending around and in contact with said wall and having a delivery end directed tangentially into said chamber only directly below said nozzles, the inlet end of said conduit being provided with a series of fresh air admission openings, and adjustable means for simultaneously varying the quantity of fresh air admitted through all of said openings.
- 55 7. In a furnace, an annular wall forming a horizontal cylindrical combustion chamber having a restricted axial outlet for hot gases of combustion at one end thereof, a series of fuel injection nozzles directed tangentially of said chamber and located only near its opposite end and above the lowermost portion of the chamber, means forming a single unobstructed annular air conducting conduit extending around and in contact with said wall, said conduit having its delivery end directed tangentially into said chamber directly beneath said nozzles and the inlet end of said conduit being provided with a fresh air admission opening, and adjustable means for varying the quantity of fresh air admitted to 60 said opening.
